UNITED STATES PATENT OFFICE.

ERNEST G. SLOMAN, OF SAN FRANCISCO, CALIFORNIA.

DESIGN FOR A SET OF PLAYING CARDS.

Application filed March 8, 1923. Serial No. 5,411. Term of patent 14 years.

To all whom it may concern:

Be it known that I, ERNEST G. SLOMAN, a citizen of the United States, residing at the city and county of San Francisco, State of California, have invented a new and original and ornamental Design for Set of Playing Cards, of which the following is a specification, reference being had to the accompanying drawing, forming part thereof.

The drawing is a plan view of a set of playing cards showing my new design.

I claim:

The ornamental design for a set of playing cards as shown.

ERNEST G. SLOMAN.
